Patented Dec. 7, 1926.

1,609,500

UNITED STATES PATENT OFFICE.

RICHARD WILHELM TERLINDEN, OF JYVASKYLA, FINLAND, ASSIGNOR TO THE FIRM:
WILH. SCHAUMLANS TARSO AKTIEBOLAG, OF JYVASKYLA, FINLAND.

METHOD FOR PRODUCING IMITATIONS OF WOODS OR INLAID WORK ON VARIOUS MATERIALS BY THE AID OF TRANSFER WORK.

No Drawing.

Application filed November 7, 1925. Serial No. 67,704.

In my former Patent Nr. 1,464,144 I have described a method for producing imitations of valuable woods and inlaid work on wood by the aid of transfer work. The present invention has for its object an improvement of this method for imitating valuable woods and inlaid work on metal, celluloid, galalith or other materials, or otherwise to provide such materials with coloured ornaments. By my invention I apply on materials of the said description a very thin film of a zapon lacquer (that is a certain kind of celluloid lacquer as is described in Otto Lueger, Lexikon der Gesamten Technik, Volume II, page 428, edited by the Deutsche Verlags-Anstalt, Stuttgart and Leipzig). This zapon lacquer is applied by a spraying, squirting or spattering apparatus, and the surface of the material is thus adapted to firmly hold a film of colour later on applied thereto. As is well known zapon lacquer adheres very firmly even on polished metal surfaces.

In order to secure a good holding connection of the film of colour with the zaponized surface the transfer pictures produced according to my Patent 1,464,144 are finally varnished or printed with a special adhesive varnish, which for instance might consist of 65 parts of strong lithographic varnish, 20 parts of liquid siccative and one part of copal lacquer. The transfer on to the metal surface or other surface is carried out then in the same manner as is described in my said original patent, that is to say, with the application of pressure and heat. After the transfer has been carried out the film of

colour is again hardened by a zapon lacquer applied by the aid of a squirting or spattering apparatus. 40

I claim:

1. A method for producing imitations of woods or inlaid work on metal, celluloid, galalith or other materials, comprising, coating the material with a film of zapon lacquer 45 to adapt it for holding a film of colour, and applying to the coated surface a transfer picture that has had the face thereof coated with an adhesive varnish and then transferring said picture to the said material. 50

2. A method for producing imitations of woods or inlaid work on metal, celluloid, galalith or other materials according to claim 1, comprising the additional step that the coloured film is hardened after being 55 transferred by applying thereto a film of zapon lacquer.

3. A method for producing imitations of woods, or inlaid work on metal, celluloid, galalith or other materials according to 60 claim 1, characterized in this that the adhesive varnish consists of 65 parts of strong lithographic varnish and 20 parts of liquid siccative copal lacquer.

4. A method for producing imitations of 65 woods or inlaid work on metal, celluloid, galalith or other materials as claimed in claim 1, including the additional step that the picture is transferred by the application of pressure and heat. 70

In testimony whereof I have signed my name to this specification.

RICHARD WILHELM TERLINDEN.
